ABSTRACT OF THE DISCLOSURE

Two known compounds, 1,2,3,4,8,9-hexahydro-3-methylpyrido[4',3':2,3]indolo[1,7-ab][1]benzazepine and 3-ethyl - 1,2,3,4,8,9-hexahydro-3-ethylpyrido[4',3':2,3]indolo[1,7-ab][1]benzazepine, are effective both as minor tranquilizers (anxiolytics) and as major tranquilizers (antipsychotics). As minor tranquilizers they are effective at non-ataxic doses, and are not likely to cause addiction when abused. Addition salts of these compounds with pharmaceutically acceptable organic or inorganic acids can be used with the same effect.

CROSS-REFERENCE TO RELATED APPLICATION

This is a continuation-in-part of my copending application Ser. No. 170,991, filed Aug. 11, 1971, now abandoned.

BACKGROUND OF THE INVENTION

This invention relates to the use of 1,2,3,4,8,9-hexahydro - 3 - methylpyrido[4',3':2,3]indolo[1,7-ab][1]benzazepine (Compound I) and of 3-ethyl-1,2,3,4,8,9-hexahydro-3-ethylpyrido[4',3':2,3]indolo[1,7-ab][1]benzazepine (Compound II) both as minor tranquilizers (anxiolytics) and as major tranquilizers (antipsychotics).

U.S. 3,457,271 (to Cohen et al.) discloses a class of organic compounds of the generic Formula 1:

(1)

where R' is a straight or branched-chain alkyl having 1-7 carbon atoms. These compounds are said to have utility as antidepressants.

U.S. 3,373,168 (to Cohen et al.) is directed to a process for the preparation of compounds of Formula 1, wherein the last intermediates have the following Formula 2:

(2)

where R' has the same meaning as in Formula 1.

This patent discloses that the intermediate of Formula 2, in which R' is methyl, and its acid addition salts, have "a powerful antiserotonin and antihistamine effect."

2

South African Pat. 680,169 (to Cohen et al.) discloses a class of compounds having the following Formula 3:

(3)

where R'' is hydrogen or a straight-chain alkyl group having no more than 4 carbon atoms.

These compounds and their acid addition salts possess a "marked depressant activity on the central nervous system and are useful as sedatives and tranquilizers."

None of the above references discloses or suggests that the compounds of Formula 2 in which R' is methyl or ethyl themselves have tranquilizer activity, much less that they can function as either minor tranquilizers (anxiolytics) or as major tranquilizers (antipsychotics).

General, nonselective central nervous system depressants are one class of drugs well recognized in the art [L. S. Goodman and A. Gilman (Eds.), *The Pharmacologic Basis of Therapeutics*, 4th ed., The Macmillan Co., N.Y., 1970]. Included in this category the anesthetic gases and vapors, aliphatic alcohols and the barbiturates and related sedative-hypnotic drugs. These agents share the common property of depressing all excitable tissue.

Also well recognized in the art is another class of depressant drugs known as selective central system depressants [*ibid*, page 40]. In contrast to the nonselective depressants, these drugs selectively affect particular central nervous system functions. Included in this category are major tranquilizers such as the phenothiazines, and minor tranquilizers exemplified by the benzodiazepins. The former, also known as antipsychotics, are used mainly in schizophrenia and other psychoses, while the latter, also known as anxiolytics, are effective in behavioral states characterized by anxiety and tension.

Most commonly used drugs, whether minor tranquilizers or major tranquilizers have undesirable side effects, including ataxia and physical dependence. There often also are undesirable pharmacological side effects which limit their usefulness, such as jaundice, parkinsonism, dyskinesia, faintness, palpitation, dry mouth, and so on.

There is, therefore, a need in the art for additional psychotherapeutic agents which would have fewer side effects than those used today and which would be effective for the treatment of either neuroses or psychoses.

SUMMARY OF THE INVENTION

According to the present invention, it has now been discovered that compounds having the Formula 2 above, in which R' is methyl or ethyl, are useful psychotropic agents which can be used in warm-blooded animals either as minor tranquilizers or as major tranquilizers.

While in U.S. Pat. 3,373,168 there compounds are named 11-methyl- (and 11-ethyl-) 5,6,10,11,12,13-hexahydro-1-benzazepino[3,2,1 - hi]pyrido[4,3 - b]indole, and displayed as in above Formula 2, the preferred names,

based on the 1957 IUPAC Rules, in which the structure is displayed and numbered as in Formula 4 below: system depressants, such as ataxia. Of particular interest

where R is methyl or ethyl, are 1,2,3,4,8,9-hexahydro-3-methylpyrido[4',3':2,3]indolo[1,7-ab][1]benzazepine (Compound I) and 3-ethyl-1,2,3,4,8,9-hexahdropyrido[4',3':2,3]indolo[1,7-ab][1]benzazepino (Compound II), respectively; rings D and E form the benzazepino portion of the molecule; rings B and C form the indolo portion; and ring A forms the pyrido portion.

In addition to the free bases themselves, their addition salts with pharmaceutically acceptable organic or inorganic acids also can be used with the same effect.

DETAILED DESCRIPTION OF THE INVENTION

The compounds of Formula 4 in which R is methyl may be made by a number of processes, for example, by the process disclosed in U.S. 3,457,271, wherein N-amino-iminodibenzyl hydrochloride is treated in ethanol with 1-methyl-4-piperidone; the mixture is heated, then saturated with dry hydrogen chloride; the solvent is evaporated; the residue is dissolved in water; the solution is made alkaline; and the product is extracted with chloroform. It is recovered as a solid material which can be recrystallized as a white product melting at 152-153°C. The hydrochloride is reported to have a melting point of 262-264°C. The compound of Formula 4 in which R is ethyl can be prepared in the same manner. According to U.S. 3,457,271, its melting point is 94-95°C. and the melting point of the hydrochloride is 276-277°C.

Other addition salts of the above compounds with pharmaceutically acceptable organic or inorganic acids can be prepared and used instead of the free bases. Such salts are normally more water soluble. Representative acids which can be used for this purpose include hydrochloric, hydrobromic, sulfuric, sulfamic, phosphoric, nitric, maleic, fumaric, benzoic, ascorbic, citric, pamoic, succinic, methanesulfonic, ethanesulfonic, acetic, oxalic, propionic, tartaric, salicylic, gluconic, lactic, malic, mandelic, cinnamic, citraconic, aspartic, stearic, palmitic, itaconic, glycolic, p-aminobenzoic, glutamic, and toluenesulfonic acids.

The compounds of the present invention, when administered to warm-blooded animals in effective psychotropic doses, do not produce certain of the undesirable side effects commonly associated with prior art central nervous system depressants, such as ataxia. Of particular interest is the fact that these compounds, which possess both minor and major tranquilizer activities, are not likely to cause addiction when abused, because the resulting major tranquilizer effect would be considered very undesirable by the subject. Indeed, it is well known that major tranquilizers are not subject to abuse.

The free bases of Formula 4 are substantially insoluble in water. They are best administered orally at a level of about 0.3 to 30.0 mg. per kilogram of body weight of the animal. At the lower doses, up to about 10 mg. per kilogram of body weight, they exhibit predominantly minor tranquilizer (anxiolytic) activity. At a higher level, their effect is predominantly antipsychotic. The usual dosage required to produce a major tranquilizer effect is about 1-30 mg. per kilogram of body weight. The rel-

atively broad overlap between the minor tranquilizer and major tranquilizer ranges is due to differences among various animal species.

Addition salts of Compounds I and II with pharmaceutically acceptable organic or inorganic acids are water-soluble and can be administered by subcutaneous or intramuscular injection. The dosage employed in such cases would be lower, generally within the range of 0.1 to 10 mg. per kilogram of body weight.

10 The pharmacological evaluation of the compounds of this invention shows that they exhibit typical major tranquilizer activity as evidenced by dose-dependent antagonism of amphetamine hyperactivity in mice, antagonism of apomorphine and amphetamine stereotype in rats, blockade of conditioned avoidance responses (C.A.R.) in mice and rats, and taming of rhesus monkeys. Most surprisingly, they also exhibit minor tranquilizer activity, manifested by antagonism of an approach-avoidance ("conflict") situation in rats, and decreased fear and increased approach-behavior in the rhesus monkey. The techniques employed in the pharmacological evaluation of Compounds I and II are described below, each one preceded by the abbreviation used at the head of the column of the following table in which the quantitative results are listed:

Screen (Results given in mg./kg. p.o./mouse)

Mouse screen: The minimal effective dose (MED) is the lowest oral dose producing an obvious decrease in locomotor activity, using observational techniques. Groups of 3 mice are given decreasing oral doses at 0.5 log intervals (300, 100, 30 . . . etc.) until no behavioral effects are evident. Decrease of locomotor activity is indicative of general central nervous system depressant activity.

A.A. (Results given in mg./kg. p.o./mouse)

Mouse anti-amphetamine activity: Groups of 5 mice are given d-amphetamine sulfate 5 mg./kg. s.c. 1 hour after oral administration of graded doses of test compounds. The mice are placed in photocell activity units immediately after amphetamine administration and locomotor activity is recorded for 60 minutes. The ED₅₀ is calculated as the dose causing a 50% reduction in locomotor activity relative to the activity of the amphetamine-treated control mice. Amphetamine antagonism at non-toxic doses appears to correlate with major tranquilizer activity in man.

C.A.R. (Results given in mg./kg. p.o./mouse,
mg./kg. p.o./rat)

Mouse and rat conditioned avoidance response: Mice and rats are trained to jump out of a pit onto a ledge to avoid shock when presented with a light and sound conditioned stimulus. The animals are tested 1, 2, and 4 hours after administration of the test compound. Three to 4 dose levels and groups of 4-8 animals/dose are used. The ED₅₀ is the dose producing a block of the C.A.R. in 50% of the animals. Blocking of the C.A.R. at non-toxic doses appears to correlate with major tranquilizer activity in man.

Taming (Results given in mg./kg. p.o./monkey)

Rhesus monkey taming effects: Compounds are administered orally to groups of 6 rhesus monkeys. The behavior of the animals is then evaluated by observational means. Taming effects are determined by the ability of the observer to approach and touch the monkey. Compounds with major tranquilizer activity in man can produce a state of passive tameness in the rhesus monkey wherein it can be touched without provoking any of the threatening or aggressive behavior seen in the normal animal. The MED is the minimal oral dose at which some taming effect can be observed.

Conflict (Results given in mg./kg. p.o./rat)

Rat conflict (approach-avoidance) test: Food deprived rats are trained to pass from one compartment to an adjacent one to obtain food. The training consists of 3 exposures to the test situation on day one of the experiment. The rats are given limited (1-2 hr.) free access to food in their home cages on day one and are then food deprived for at least 18 hours. On day two of the experiment, the rats are given a control exposure to the test situation followed by a second exposure after $\frac{1}{2}$ to 1 hour in which they are shocked after crossing and eating. Groups of 6-8 rats are then dosed orally with solvent or test compound and then re-exposed to the test situation after 1 or 2 hours.

Compounds showing minor tranquilizer (anxiolytic) activity in man such as diazepam and meprobamate produce an apparent decreased fear in the test animals so that they cross to obtain food despite having received a shock earlier. This effect is dose-related (and the MED is the minimum dose at which this effect is obtained); rats dosed with solvent only consistently show a high level of fear as evidenced by decreased mobility and absence of feeding when placed in the test situation after receiving a shock.

Approach (Results given in mg./kg. p.o./monkey)

Rhesus monkey approach effects: Compounds are administered orally to groups of 6 rhesus monkeys. The behavior of the animals is then evaluated by observational means. Approach effects are examined by determining whether a monkey shows decreased fear as evidenced by reaching out for food or objects or coming closer instead of the withdrawal behavior that is seen in the untreated monkey. Compounds influencing this type of behavior have been shown to be useful in man as minor tranquilizer (anxiolytic) agents. The MED is the oral dose at which the animals show signs of decreased fear.

Quantitative results obtained with Compounds I and II, using the methods described above, are compared in the following table with results obtained with chlorpromazine, a well-known major tranquilizer, and with diazepam, a well-known minor tranquilizer.

TABLE

Compound	Screen (mouse) MED	A.A. (mouse) ED ₅₀	C.A.R. (mouse) ED ₅₀	C.A.R. (rat) ED ₅₀	Taming (monkey) MED	Conflict (rat) MED	Approach (monkey) MED
3-R-1,2,3,4,8,9-hexahydropyrido[4',3':2,3]indolo[1,7-ab][1]benz-azepine (Formula 4):							
R=CH ₃ (Compound I)-----	10-30	10	20	30	10-20	10-20	1-3
R=C ₆ H ₅ (Compound II)-----	30-100	10	>40	>40	20-30	10-20	(*) 1
Chlorpromazine-----	3-10	5	5	10	10-30	I	I
Diazepam-----	3-10	ic	Ia	Ia	I	I	3-10

*=indicates compound has not been evaluated in this test.

^=active, but also causes ataxia at this dose.

I=inactive.

Ia=inactive at doses not producing ataxia.

ic=inconsistent results.

The above results show that both Compounds I and II are active minor as well as major tranquilizers, which compare well with the known standards.

Some addition salts of the compounds having Formula 4 with pharmaceutically acceptable inorganic or organic acids are water-soluble and can be administered by subcutaneous or intramuscular injection. The dosage employed in such cases would be lower and generally would be within the range of 0.1 to 10 milligrams per kilogram of body weight. The usual dosage for minor tranquilizer activity is 0.3 to 10 mg./kg. per o.s. and for major tranquilizer activity 1 to 30 mg./kg. per o.s. The relatively broad overlap between the minor tranquilizer and major tranquilizer ranges is due to differences among various animal species. The compounds of the present invention can be formulated into compositions comprising a compound of Formula 4 or a pharmaceutically acceptable acid addition salt thereof together with a pharmaceutically acceptable carrier. The carrier may be either a solid or liquid, and the compositions can be in form of tablets,

liquid-filled capsules, dry filled capsules, aqueous solutions, non-aqueous solutions, suppositories, syrups, suspensions and the like. The compositions can, and in many cases do contain suitable preservatives, coloring and flavoring agents. Some examples of the carriers which can be used in the preparation of the products of the invention are gelatin capsules, sugars such as lactose and sucrose; starches, dextrans and cellulosics, such as methyl cellulose and cellulose acetate phthalate; gelatin; talc, stearic acid salts; vegetable oils such as peanut oil, cottonseed oil, sesame oil, olive oil, corn oil and oil of theobroma; liquid paraffin; polyethylene glycol; glycerine; sorbitol; propylene glycol; ethanol; agar; water and isotonic saline.

In preparing the compositions of the invention for pharmaceutical uses, the conventional practices and precautions are used. The composition intended for parenteral administration must be sterile, and this can be accomplished either by using sterile ingredients and carrying out the production under aseptic conditions, or by sterilizing the final composition by one of the usual procedures such as autoclaving under appropriate temperature and pressure conditions. Customary care should be exercised that no incompatible conditions exist between the active components and the diluent preservative or flavoring agent or in the conditions employed in preparation of the compositions.

The compositions of the invention can be introduced into warm-blooded animals by the oral, rectal or parenteral route. This can be done by swallowing, in the case of liquid or solid preparations; by suppositories; or by injecting the liquid preparations intravenously, intramuscularly, intraperitoneally, or subcutaneously.

Typical formulations of the type listed above which may be used for the administration of these compounds are:

EXAMPLE A

Ingredients:	Mg./tablet
1,2,3,4,8,9-hexahydropyrido[4',3':2,3]indolo[1,7-ab][1]benzazepine hydrochloride -----	15
Lactose, USP -----	183
Magnesium stearate, USP -----	2
Color (if desired) q.s.	

All of the above ingredients are passed through a suitable sieve, blended for 20 minutes, and compressed directly into tablets of 200 mg. on a suitable table press using a 11/32" punch and die.

EXAMPLE B

Ingredients:	Mg./tablet
3 - ethyl-1,2,3,4,8,9 - hexahydropyrido[4',3':2,3]indolo[1,7-ab][1]benzazepine hydrochloride -----	50
Lactose, USP -----	215
Methylcellulose, USP -----	15
Talc, USP -----	6
Starch, USP -----	10
Magnesium stearate, USP -----	4
Color (if desired) q.s.	

The lactose and active ingredient are wet granulated with a solution of methylcellulose in a blender until a satisfactory mass is achieved. The mass is dried and classi-

fied through an appropriate sieve. The remaining ingredients are passed through an 80 mesh sieve and blended with the dried granulated material. The blend is then compressed into tablets on a suitable tablet press at a weight of 300 mg. using a $\frac{3}{8}$ " punch and die.

EXAMPLE C

Ingredients:	Mg./capsule
1,2,3,4,8,9 - hexahydro - 3 - methylpyrido[4',3':2,3]indolo[1,7-ab][1]benzazepine hydrochloride	25
Lactose, USP	100
Magnesium stearate, USP	1
Colloidal silicon dioxide, N.F.	2

The combined ingredients are blended and passed through a 40 mesh sieve, and the mixture is encapsulated into a two-piece hard gelatin No. 3 capsule on a suitable encapsulating machine at a net weight of 128 mg.

EXAMPLE D

Ingredients:	Grams/liter
1,2,3,4,8,9 - hexahydro - 3 - methyl-pyrido[4',3':2,3]indolo[1,7 - ab][1]benzazepine methanesulfonate	3
Granulated sugar	600
Sodium benzoate	1
Flavor, q.s.	25
Color, q.s.	
Deionized water, q.s.	

All of the above ingredients are dissolved in water and made up to a volume of one liter.

EXAMPLE E

Ingredients:	Grams/liter
3 - ethyl - 1,2,3,4,8,9 - hexahydropyrido[4',3':2,3]indolo[1,7 - ab][1]benzazepine methanesulfonate	10
Propylparaben, USP	0.2
Methylparaben, USP	1.8
Water for injection, q.s. to 1 liter.	

Dissolve the parabens in about 800 ml. of water for injection at 80°. Cool to room temperature, add the active ingredient, and stir to dissolve. If the solution is aseptically prepared, sterile filtration through a millipore filter or other suitable retentive filter is desirable. Terminal sterilization by autoclaving may also be employed to render the product sterile.

EXAMPLE F

Ingredients:	Grams/liter
1,2,3,4,8,9 - hexahydro - 3-methylpyrido[4',3':2,3]indolo[1,7 - ab][1]benzazepine methanesulfonate	10
Propylparaben, USP	0.2
Methylparaben, USP	1.8
Sodium carboxymethylcellulose, USP (CMC)	5
Polysorbate 80, USP	1
Water for injection, q.s. to 1 liter.	

The parabens, CMC and one-half of the polysorbate 80 are dissolved in about 700 ml. of water for injection, with agitation at 80° (solution A). A slurry is made of the active ingredient, one-half of the polysorbate 80 and about 200 ml. of water for injection (slurry B). Solution A is aseptically filtered through a millipore filter to render it sterile, while slurry B is autoclaved for 30 minutes at 15 lbs. steam pressure to make it sterile. A and B are aseptically combined, brought to correct volume with sterile water for injection, and mixed to homogeneity.

I claim:

1. A method of causing a tranquilizer effect in warm-blooded animals in need of a tranquilizer by administering to said animals an effective amount of a compound selected from the group consisting of

(A) a free base having the formula

in which R is methyl or ethyl, and

(B) an addition salt of (A) with a pharmaceutically acceptable acid.

2. A method of claim 1 wherein the active ingredient is administered parenterally at a dose of about 0.1 to 10 mg. per kilogram of body weight of the animal.

3. A method of claim 1 wherein the active ingredient is administered orally at a dose of about 0.3 to 30 mg. per kilogram of body weight of the animal.

4. A method of claim 3 wherein the tranquilizer effect is an anxiolytic effect.

5. A method of claim 4 wherein the active ingredient is administered at a dose of about 0.3 to 10 mg. per kilogram of body weight of the animal.

6. A method of claim 3 wherein the tranquilizer effect is an antipsychotic effect.

7. A method of claim 6 wherein the active ingredient is administered at a dose of about 1 to 30 mg. per kilogram of body weight of the animal.
